FOOD PACKAGING CARTON

Michael Vargas, 4730 Twining St.,
Los Angeles, Calif. 90032

Filed July 25, 1969, Ser. No. 18,414

Term of patent 14 years

Int. Cl. D9—04

U.S. Cl. D9—197

Fig. 1

Fig. 5

FIG. 3

FIG. 2

FIG. 4

FIG. 1 is a perspective view of my food packaging carton showing my new design.

FIG. 2 is a side view of FIG. 1, the opposite side having the same appearance.

FIG. 3 is an end view of FIG. 1, the opposite end having the same appearance.

FIG. 4 is a top plan view of FIG. 1.

FIG. 5 is a perspective view of my design in partially opened condition.

The bottom of the food packaging carton is substantially plain and unornamented.

I claim:

The ornamental design for a food packaging carton, substantially as shown and described.
